BRUSH STRUCTURE AND HOLDER

Raymond G. Anderson, West Orange, and William T. Jacobson, Clifton, N. J., assignors to The Roto Company, a corporation of New Jersey

Application March 15, 1941, Serial No. 383,536

7 Claims. (Cl. 15—183)

Our invention relates generally to new and useful improvements in brush structures and holders therefor, as well as a new and improved method of manufacturing brushes of the type which are commonly employed in the cleaning of relatively small diameter boiler tubes, condenser tubes and the like.

It will be understood, of course, that brushes of this character have a wide application in industry apart from the beforementioned uses and that it is contemplated that the invention may be employed in any and all such environments. As presently manufactured, these brushes consist of a plurality of individual brush elements symmetrically positioned in a common holder which may be rotated by power or manual means.

In connection with a consideration of the physical characteristics imposed upon such brushes by the uses to which they are put, it is important to note that the tubes which they are employed to clean are commonly as small as 1" in diameter, so that the structure must be exceedingly compact. Furthermore, it has been found that the diametrical limitations thus imposed upon the size of the brush, preclude the possibility of successful recourse to mechanism within the brush or holder to yieldably urge its elements to brushing contact with the walls of tubes of varying diameter.

It will be obvious, however, that any slight variation in the internal diameter of the tubes would render a brush comprised of fixed elements ineffective. Hence such a structure, to be adaptable to other than very limited service must needs incorporate either provision for manual adjustment of the diameter of the brushes, or in the alternative, its elements must "float," or be otherwise so automatically flexible as to accommodate themselves to tubes of varying diameter.

Yet another practical consideration involved in the construction of the brush element, is that which results from the normal tendency of the brush to foul when utilized in the cleaning of tubes which may be coated with gums or sticky substances such as milk residue, carbohydrates, or hydrocarbons. Hence, the brush structure, as well as its holder, must be capable of disassembly and re-assembly for the purpose of cleaning and inspection of its parts. The desirability of access for repair and replacement also arises in the cleaning of scale from boiler tubes where surface conditions are sufficiently severe to result in wearing of the brushes, with an accompanying necessity for frequent renewal of parts.

Thus, it is one object of the invention, to provide a brush of the character described in which the brush elements are capable of automatically adjusting themselves to varying diameters of tubes as well as to such variations as may occur in the diameter of any given tube, for example, from the adherence of foreign matter to the interior surface of the tube.

Another object of the invention consists in the provision of a brush of the character described which adapts itself to ready assembly and disassembly for the purpose of replacing its parts.

Yet a different object resides in the provision of a brush of the character referred to, in which the individual brush elements thereof automatically act to compensate for wear so as to insure engagement with the surface to be brushed.

A further object of the invention resides in the provision of a brush structure which will be economical of manufacture, and consist of the fewest possible number of parts so as to facilitate and simplify assembly and disassembly of the unit.

Still another object consists of the provision of a new and improved brush holder, the construction of which facilitates insertion or replacement of the brushes elements.

A more specific object resides in the provision of a brush holder consisting of a main solid cylindrical body portion formed with radially extending slots having opposed parallel side walls adapted to journal the brush elements, and a single removable cap effective to render said brush elements accessible for removal and replacement.

Another object of the invention consists in the provision of a new and improved method of manufacturing brush elements of the character described, in which a succession of related but simple manufacturing operations, contribute to the economical production of a new and improved brush structure.

Other objects and advantages will be apparent in the following description, taken in connection with the accompanying drawing in which:

Fig. 1 is a perspective view of a bar utilized in the construction of a brush element.

Fig. 2 is a perspective view of the bar shown in Fig. 1, in a later stage of the manufacturing process.

Fig. 3 represents the bar of Figs. 1 and 2 in a third step of the manufacturing operation.

Fig. 4 is a cross sectional view of the bar of Figs. 1-3 inclusive, following the last step in the manufacturing process.

Fig. 5 is a perspective view of the bar of Fig. 4 showing four tufts of bristles assembled in position.

Fig. 6 is an assembly view of several brush elements in a preferred form of brush holder.

Fig. 7 is a cross sectional view of the holder and brush elements of Fig. 6, taken along the line 7-7 of the later view.

Referring now particularly to Fig. 1, in which we have illustrated an initial step in the improved method of manufacturing a brush element.

In this view, as well as in Figures 2 to 5 inclusive, the body of the brush element is illustrated in an inverted position to more clearly demonstrate the manufacturing process.

An elongated bar of substantially square cross section, is cut in equal lengths to form brush element bars 10, the inner faces of which are identified by the numeral 11, the outer or external faces being shown at 12.

The external surfaces of bar elements 10, are undercut on a radius r to form similar steps 13, of equal depth extending longitudinally from the respective ends of the bar.

The bar is next drilled to form a series of equally spaced apertures 14, the axes of which preferably coincide with the longitudinal axis of the bar.

These apertures extend completely through the bar and are utilized as will hereinafter appear, to receive independent tufts of bristles. Of course it will be understood that the apertures 14 may be drilled singly, or in the alternative, where gang drilling equipment is used, they may be formed in multiples prior to cutting of the stock material into the finished lengths illustrated by the piece 10.

Subsequent to the beforementioned drilling operation, the bars 10 are milled on a line corresponding with their longitudinal axes to form a narrow kerf, or slot 15, which extends from the under surface 11 to a line 16, substantially coincident with the median line through the center of the bar. Here again, it will be apparent that this operation may be automatically accomplished prior to cutting of the bar stock into the lengths shown in the drawings or, the individual pieces may be successively fed into operative engagement with a milling cutter.

Referring now to Fig. 3, which illustrates the bar following the last step in its manufacturing operation, it will be noted that the opposite parallel side walls 17 and 18 are cut from their inner edges, as for example, by milling or grinding, to form angularly disposed converging faces 19 and 20. The faces 19 and 20 will be seen to intersect the lines formed by the kerf 15 in the under surface of the bars so as to provide the appearance of a succession of spaced parallel webs 21 through each one of which the kerf 15 extends downwardly to the line 16. Like the previously described manufacturing operations, the formation of the inclined faces 19 and 20 lends itself to a simple automatic machine operation which may be accurately and inexpensively formed as the last one of a succession of related steps.

As fully shown in Figs. 4 and 5, individual tufts of looped bristles 22 are inserted in the apertures 14 from the external surface 12 of the bar.

The tufts are forced through the respective apertures until the inner portions of their loops clear the line 16 of the bottom of slot 15, whereupon a rigid pin 23 is passed through the loops,

its ends terminating substantially flush with the ends of the bar. The tufts are now drawn down upon the pin 23, whereupon a second overlying rigid pin or bar 24, is positioned in the slot 15 so as to retain the tufts in assembled position in the bar. The rod 24 may be rigidly retained in tuft holding position in the slot 15, as for example, by soldering or welding. We prefer, however, to peen the end apices defined between the inclined surfaces 17 and 18, and the side walls of the slot 15 as shown by the numerals 25 and 26, thus forming a solid and indestructible unit in which the tufts of bristles are satisfactorily prevented from dislodging. Furthermore, as an added safeguard against the possibility of the rod 24 being dislodged intermediate its ends, we may peen the intermediate pairs of apices 27 and 28 which are formed between successive apertures 14, as a result of the combined drilling and edge milling operations. Thus, the rod 24 is capable of being held at five separate points throughout its length in each bar containing four tufts of bristles.

Now coming to the construction of the brush holder illustrated in Figs. 6 and 7:

The holder includes a main body member 30 of circular cross section which may accordingly be manufactured from a stock rod material. This body member is milled to form a plurality of longitudinally extending radial slots 31 the number being dependent upon the number of brush elements to be employed.

As shown particularly in Fig. 7, the slots 31 comprise inwardly extending parallel side walls 32 and 33, spaced apart to freely journal the side faces 17 and 18 of the brush elements 10.

Adjacent their inner ends, the side walls 32 and 33 of slots 31 converge on an angle of substantially 45 degrees as shown at 34 and 35, to define angles similar to the angularity of the faces 19 and 20 of the brush elements 10.

It will now be observed that the economy of space which is effected in the formation of the faces 19 and 20 of the brush elements, as distinguished from bending a solid wall of the bar into engagement with the bristles, results in relatively greater movement of the brush elements from their extreme inner to their outer positions, as defined by the solid and broken outlines in Fig. 7. In other words, the construction of the brush elements forms a relatively shallower unit than has heretofore been provided, and this feature in turn makes for a greater range of usefulness of the unit because it is capable of adapting itself to a wider range of tube diameters. In the construction illustrated, for example, the brush unit is capable of operation in tubes ranging from $\frac{1}{8}$ of an inch in diameter to $1\frac{1}{8}$ in diameter with maximum efficiency throughout all intermediate sizes of tubes.

The cylindrical surface of the body member is undercut at its forward or leading end as shown at 36 to receive a circular end cap 37 the internal cylindrical surface of which is formed on the radius r . Cap 37 may be permanently secured to the body by swaging or any other desired means.

The rear, or following end of the body member, is similarly undercut as shown at 38, to receive a removable cap 39, which, like cap 37, is formed with an internal surface having the radius r . Cap 39 is additionally provided with an axial aperture permitting free sliding movement on a threaded stud 40 formed integrally with the body member.

A nut 41, arranged to threadably engage the stud 40, is effective to hold the cap 39 in position.

Referring again to Figs. 5 and 6, it will now be apparent that the undercut ends 13 of the brush elements, engage the forward fixed cap 37 and the removable cap 39 respectively, when centrifugal force acts to throw the brush elements to the outer limits of their movement.

Furthermore, it will be seen that removal of the nut 41, followed by sliding of the cap 39 from the stud 40 will permit removal of the brush elements for cleaning or replacement.

It will additionally be observed that the unitary character of the body 30 with its accompanying freedom from loose parts will greatly facilitate disassembly and reassembly of the structure.

The provision of the solid walls 31 and 32 extending throughout the length of the side walls of the bars 10 insure freedom of action of the brushes without any accompanying possibility of their becoming "cocked" and thus bound against free sliding movement in their respective slots. Hence, the brush elements will always freely operate under the influence of centrifugal force to move outwardly to the position in which their bristles engage the surface of the tube to be cleaned.

We claim as our invention:

1. The method of forming a brush element which comprises the steps of drilling an elongated bar to provide a plurality of equally spaced apertures extending in a line coincident with the center line of said apertures to a depth corresponding substantially with the median line thereof to form a narrow kerf, then cutting away the inner parallel edges of the bar on an angle of substantially 45 degrees to provide in conjunction with the walls of said kerf, and said apertures, a plurality of separate pairs of apices spaced along the bar in pairs, then feeding tufts of looped bristles into each of said apertures from the external surface of the bar to a point where the interior loop of the tufts is spaced below the beforementioned median line of the bar, then passing a pin along the bottom of said kerf and through said loops, drawing said tufts of bristles outwardly into engagement with said last mentioned pin, laying a second pin in said kerf in overlying engagement with the outer loops of said bristles, and finally, peening the beforementioned apices formed between the walls of said kerf and the cut away edges of the bar to a wedge of said last mentioned pin in said kerf.

2. The method of forming a brush element which comprises the steps of drilling an elongated bar to provide a plurality of apertures extending therethrough, then milling the internal face of the bar throughout its length on a line intersecting said apertures to form a narrow kerf, then cutting away the inner parallel edges of the bar on an angle of substantially 45 degrees, to provide in conjunction with the walls of said kerf, a pair of apices at each end of the bar, then feeding tufts of bristles into each of said apertures from the external surface of the bar to a point where the interior loop of the tufts is spaced below the bottom line of said kerf, then passing a pin along the bottom of said kerf and through said loops, drawing said tufts of bristles outwardly into engagement with said last mentioned pin, laying a second pin in said kerf in overlying engagement with the outer loops of said bristles and finally, securing said last mentioned pin in

position in said kerf to prevent dislodgment of said bristles.

3. A brush element for boiler tube cleaners, comprising in combination, a bar having outer, spaced parallel side walls, and inner converging side walls which merge with said parallel walls on a line substantially coincident with the plane of the median line of the bar, said bar being formed with a plurality of apertures, the respective axes of which define a plane parallel to the planes of said beforementioned side walls, said bar also being formed with a kerf extending longitudinal thereof from the apex defined by said converging side walls to a line substantially coincident with the median line through said bar, a tuft of looped bristles arranged in each said aperture, a pin in the bottom of said kerf and extending through said loops to prevent said tufts of bristles from being dislodged in one direction, a second pin in said kerf, in overlying relation with respect to said loops of said tufts of bristles to prevent dislodgment of said bristles in a second direction and means to prevent said last mentioned pin from being dislodged from said kerf.

4. A brush element for tube cleaners, comprising in combination, an elongated bar having spaced parallel side walls to define bearing surfaces, said bar being formed with a plurality of apertures, the respective axes of which lie parallel to the planes of said side walls, and a longitudinal kerf intersecting said apertures, tufts of bristles arranged in each said aperture, and a bar rigidly supported in said kerf in overlying relation with respect to said bristles to prevent dislodgment thereof.

5. A brush holder of the character described, comprising in combination, a cylindrical body member, said body member being formed with a plurality of radially extending slots, said slots being characterized by an outer portion consisting of parallel side walls and an inner portion in which said side walls converge toward the axis of said body member, a cap rigidly secured to one end of said body member, and a second cap removably secured to the opposite end of said body member.

6. A brush holder of the character described, comprising in combination, a solid cylindrical body member, said body member being formed with a plurality of longitudinally extending radial slots, said slots being characterized by an outer portion consisting of parallel side walls and an inner portion in which said side walls converge toward the axis of said body member, a cap rigidly secured to one end of said body member and a second cap removably secured to the opposite end of said body member.

7. A brush element for boiler tube cleaners comprising in combination, a bar, said bar being formed with a plurality of apertures, the respective axes of which define a plane extending parallel to the longitudinal axis of the bar, said bar having a longitudinal kerf intersecting said apertures, a tuft of looped bristles arranged in each said aperture, a pin lying in the bottom of said kerf and extending through said loops to prevent said tufts of bristles from being dislodged in one direction, a bar in said kerf, in overlying relation with respect to said tufts of bristles to prevent dislodgment of said bristles in a second direction, and means to prevent said bar from being dislodged from said kerf.

RAYMOND G. ANDERSON.
